UNITED STATES PATENT OFFICE.

CHARLES C. ABBOTT, OF PITTSFIELD, MASSACHUSETTS, ASSIGNOR TO TRIUMPH VOTING MACHINE COMPANY, OF PITTSFIELD, MASSACHUSETTS, A CORPORATION OF NEW JERSEY.

PRIMARY-VOTING MECHANISM.

1,116,360.

Specification of Letters Patent.

Patented Nov. 10, 1914.

Original application filed February 13, 1911, Serial No. 608,383. Divided and this application filed January 2, 1912. Serial No. 669,252.

To all whom it may concern:

Be it known that I, CHARLES C. ABBOTT, a citizen of the United States, residing at Pittsfield, county of Berkshire, State of Massachusetts, have invented an Improvement in Primary-Voting Mechanism, of which the following is a specification.

This invention relates to voting machines and has for its object to provide mechanism adapted for use in primary voting, the same being a division of a prior application filed by me February 13, 1911, Serial Number 608,383.

The present invention contemplates the provision of means for locking all of the voting members of a voting machine except those corresponding to the nominees of the party of the voter, said last named voting members being unlocked and in a condition to be operated by the voter whether said members occupy one or a plurality of lines. I have further made provision whereby the locking means for the voting members may be controlled or adjusted to unlock the voting members corresponding to any desired party, all others remaining locked.

With the above and other objects in view I have devised the novel mechanism which I will now describe, referring to the accompanying drawings forming a part of this specification and using reference characters to indicate the several parts.

Figure 1 is a front elevation, partly broken away, of the voting members, connecting bars, locking bolts, and adjacent frame parts. Fig. 2 is a plan view, partly in section, of the primary locking mechanism and one line of voting members. Fig. 3 is a rear elevation, partly broken away, of the primary locking mechanism. Fig. 4 is an elevation of the key bar as viewed from the left in Fig. 3. Fig. 5 is an enlarged detail elevation of a portion of Fig. 4 with the locking bolt in section substantially on the line 5—5, Fig. 2, said view showing the form of the keys and the manner of securing the same in position on the key bar, and also illustrating diagrammatically the operation of these keys upon the locking bolts. Fig. 6 is a detail elevation of the latch for locking the key bar operating shaft in position.

The invention is herein shown as applied

to a machine of the general type shown and disclosed in Letters Patent No. 914,006, granted to me March 2, 1909. The machine shown in said patent is a horizontal machine, so called, in which the names of party candidates are placed in horizontal lines, called party lines, and the names of all candidates for the same office are placed in vertical columns, called office columns, although of course the mechanism may be arranged otherwise if preferred. It will, of course, be understood that there may be any suitable number of lines of voting members and any suitable number of columns (i. e. any number of voting members in each line) according to the requirements.

12 denotes the framework of the machine which is preferably constructed of sheet metal forming a casing and providing the necessary supports, guides and bearings for the various parts of the machine.

13 denotes the voting devices or members as a whole, these voting members comprising oscillatory shafts journaled in the framework and having voting levers or keys 14 lying outside the machine in front. Turning of these voting members from the non-voting to the voting position, i. e. rotating them in a clockwise direction through a suitable angle from the position shown in Fig. 1, places them in a position to cause an operation of suitably arranged counters corresponding in number to the voting members. This counting mechanism is not shown herein as it forms no portion of the present invention and is fully disclosed in my prior patent above referred to.

15 denotes connecting bars corresponding in number with the party lines of the machine.

16 denotes arms on the voting member shafts, said arms carrying pins 17 which pass through slots 18 in the bars 15.

The voting mechanism thus far referred to is, in a general way, well known in the art and will, it is thought, be understood without further description. The specific construction of the voting members and the parts operated thereby form no portion of the present invention.

The normal or non-voting position of the parts is shown in Figs. 1 and 2. With the

parts in this position the pins 17, carried by the arms 16 of the voting members, are in engagement with the left ends of the slots 18 in the bars 15, as shown in Fig. 1. None 5 of the voting members in any line can be turned into voting position, as above described, without causing a movement of the corresponding connecting bar from right to left.

10 20 denotes primary locking bolts or members. These bolts are equal in number to the number of lines of voting members, are guided in suitable parts of the framework, and are movable from an inoperative or 15 retracted position into an operative position in which their forward ends are adjacent studs 19 riveted to the ends of the connecting bars 15. As shown in Figs. 1 and 2 the connecting bars 15 are all in the extreme position toward the right, and each of the bolts 20, when in operative position as shown in Fig. 2, serves to lock the corresponding bar 15 in its extreme position, and, by engagement of the pins 17 with the 25 ends of the slots 18, to lock the voting members in the corresponding line in non-voting position.

21 (see Figs. 3 and 4) denotes a key bar or carrier slidably mounted in a guideway 30 formed by the rear of the machine casing and a cover plate 22 secured thereto, said cover plate having an index opening 23. The rearward ends of the bolts 20 pass through openings in the rear wall of the 35 casing and through opposite openings in the cover plate 22 and are preferably provided outside said cover plate with heads 24.

25 denotes party markers arranged according to statutory provision and each 40 designated by an identifying symbol, herein shown as letters, "A," "B," "C," etc. The key bar 21 is shown as composed of three plates riveted together, the central plate being provided with a series of projecting 45 lugs or teeth 26. Said lugs or teeth may, for convenience, be considered as arranged in groups, there being a number of teeth in each group equal to the number of party lines, and the individual teeth of each 50 group being designated on the key bar by symbols corresponding to the symbols displayed by the party markers, as shown in Fig. 3. The several groups are further distinguished by designating characters, preferably numerals, "2," "3," "4," etc.

55 27 (see Figs. 2 and 3) denotes a shaft journaled in the framework and provided outside the casing with an operating knob or handle 28. The shaft 27 carries a pinion 60 29 adapted to coöperate with rack teeth 30 formed on the key bar 21. By rotating the shaft 27 the key bar can be moved longitudinally to bring any desired symbol opposite the index opening 23.

65 31 denotes a washer loosely surrounding

the shaft 27 and fixed against rotation to the framework.

32 denotes a second washer mounted on the shaft 27 for rotation therewith but movable longitudinally thereof.

33 denotes a collar pinned to the shaft 27 and between which and the washer 32 is interposed a spring 34. The washers 31 and 32 are formed with interengaging angular recesses and projections and, being held in yielding engagement with one another by the spring 34, form a yielding lock for normally holding the shaft in certain predetermined angular positions. These positions are such as will hold the key carrier 21 with one of the symbols carried thereby exactly opposite the index opening 23. The shaft 27 is longitudinally movable in its bearings to carry the pinion 29 into and out of engagement with the rack 30.

35 (see Figs. 2 and 6) denotes a latch pivoted at 36 to the framework and provided with a projection 37 adapted to occupy a position between the collar 33 and the framework to hold the shaft 27 against longitudinal movement and consequently maintain the pinion 29 in engagement with the rack 30.

38 denotes a spring for normally holding the latch 35 in locking position.

39 denotes members carried by the bar 21, which members, for convenience, I denominate "keys" since they perform the function of operating the locking bolts or members 20 to lock and unlock the respective lines of voting members, as will be explained. As shown the keys comprise flat strips of metal bent to form angular offsets or cam portions 40. The keys may be applied to the key carrier in any required position and are held in place thereon by engagement with the teeth 26, the offset portion 40 embracing one of these teeth, as shown most clearly in Fig. 5. The primary locking members 20 are provided with notches 41 adapted to receive the edges of the keys 39.

The operation of the keys 39 in locking and unlocking the several lines of voting members will best be understood from Fig. 5 taken in connection with Fig. 2. In the former figure a bolt 20 is shown in full lines in its operative or locking position and in dotted lines in its inoperative or retracted position. It will be understood that the bolts 20 are guided for horizontal movement only, and that the key bar is moved vertically to effect the movement of these bolts. For convenience of illustration, however, in Fig. 5 the key bar has been represented as in one position only and the bolt 20 shown in two different vertical positions, but it will be obvious that the relative horizontal positions of the bolt and key bar

would be the same were two different vertical positions of the key bar rather than of the bolt shown in this figure.

When the straight portion of any key 39 is in engagement with the notch 41 of the corresponding locking member or bolt, as shown in full lines in Fig. 5, said member will be projected forwardly into locking position with its forward end in a position to 10 be engaged by the stud 19 on the connecting bar 15, as shown in Fig. 2, thereby locking the corresponding party line. When the key bar 21 is moved (that is raised from the position shown in Fig. 5) to bring the cam portion 40 into engagement with the notch 41, as shown in dotted lines in Fig. 5, the locking member is retracted and its forward end carried out of the position shown in Fig. 2, thereby unlocking the corresponding 20 party line.

The several keys 39 (see Fig. 3) are preferably provided with designating characters corresponding to the designating characters or numerals provided on the key carrier 21 to indicate the respective groups of teeth 26. The keys are applied to the key carrier in such a manner that when the symbol "A" on the key carrier is opposite the index opening 23 party line "A" will be unlocked 30 and the remaining party lines locked. When the knob 28 is turned to bring the symbol "B" opposite the index opening party line "B" will be unlocked, party line "A" will be locked, and the other party lines will remain 35 locked. In this manner any desired party line can be unlocked leaving the other party lines locked. This, in the construction shown, is accomplished by placing the key "1" with its offset portion 40 on the tooth 26 designated by "A" (as shown the first group of teeth is not indicated by numerals, which may, however, be applied if desired), the key "2" with its offset portion 40 on the tooth "B", the key "3" on the tooth 40 "C", and so on. Should any party occupy more than one line the keys will be correspondingly arranged to cause both or all of these lines to be simultaneously locked and unlocked. For example, should the 45 party "B" occupy the second and third lines, key "1" will be placed with its offset portion on tooth "A," key "2" on tooth "B," key "3" on tooth "B," key "4" on tooth "C," and so on as will be obvious.

In order that the keys may at all times be in engagement with their respective notches these keys are preferably formed with their offset or cam portions 40 at a progressively varying distance from their upper ends, as 50 clearly shown in Figs. 3 and 4.

In order to remove the key carrier from the machine for the purpose of arranging the keys the latch 35 is raised permitting the spring 34 to move the pinion 29 out of 60 engagement with the rack 30. The key car-

rier may then be withdrawn downwardly from beneath the cover plate 22.

The operation of the machine has, it is thought, been fully explained in connection with the foregoing description of its construction but may be briefly summarized as follows: Let it be assumed that the party markers 25 have been put in place and the keys 39 applied to the key bar 21 in accordance with the requirements and as heretofore 70 fully explained. A primary voter having entered the polling place and declared his party, the custodian turns the knob 28 until the symbol corresponding to the party so declared appears at the index opening 23. 75 When this has been done the primary locking member or members 20 which control the line or lines of voting members occupied by the party in question have been withdrawn by the engagement of the cam portions 40 of the corresponding keys with the notches 41 of said members 20, while all other locking members are held by the straight portions of the corresponding keys with their forward ends in positions to engage the studs 19 carried by the bars 15 of the other party lines thereby locking all voting members except those in the lines occupied by the candidates for whom the primary voter is entitled to vote. 85

Having thus described my invention, I claim:—

1. The combination with lines of voting members, of primary locking mechanism including means for locking the voting members in the several lines, a member controllable independently of said voting members and provided with means for controlling said locking means to lock or unlock the voting members in any line or lines, and 95 a cover plate for guiding said member.

2. The combination with lines of voting members, of primary locking mechanism including locking members for locking the voting members in the several lines, and a key carrier provided with keys for controlling said locking members to lock or unlock the voting members in any line or lines, said key carrier having a plurality of groups of attaching devices for said keys, the devices 100 of the several groups being indicated by different designating characters. 110

3. The combination with lines of voting members, of primary locking mechanism including locking members for locking the voting members in the several lines, and a key carrier provided with keys for controlling said locking members to lock or unlock the voting members in any line or lines, said key carrier having a plurality of groups of 115 teeth for engaging said keys and the teeth of the several groups being indicated by designating characters. 120

4. The combination with lines of voting members, of primary locking mechanism in- 130

cluding locking members for locking the voting members in the several lines, and a key carrier provided with keys for controlling said locking members to lock or unlock the voting members in any line or lines, said key carrier having a plurality of groups of attaching devices for said keys, the devices of the several groups being indicated by different designating characters, and the keys having designating characters corresponding to the characters on the key carrier.

5. The combination with lines of voting members, of primary locking mechanism including locking members for locking the voting members in the several lines, and a key carrier provided with keys for controlling said locking members to lock or unlock the voting members in any line or lines, said key carrier having a plurality of groups of attaching devices for said keys, and the several devices of each group being indicated by different identifying symbols.

6. The combination with lines of voting members, of primary locking mechanism including locking members for locking the voting members in the several lines, and a key carrier provided with keys for controlling said locking members to lock or unlock the voting members in any line or lines, said key carrier having a plurality of groups of attaching devices for said keys, the devices of the several groups being indicated by different designating characters and the several devices of each group being indicated by different identifying symbols.

7. The combination with lines of voting members, of primary locking mechanism including members for locking the voting members in the several lines, a member provided with means for controlling said locking members to lock or unlock the voting members in any line or lines, and a cover plate for guiding said member and having an index opening, said member being provided with identifying symbols adapted to be brought successively opposite said index opening to indicate the line or lines of voting members which are unlocked.

8. The combination with lines of voting members, of primary locking mechanism including locking members for locking the voting members in the several lines, a key carrier provided with keys for controlling said locking members to lock or unlock the voting members in any line or lines, and a cover plate for guiding said key carrier and having an index opening, said key carrier having a plurality of groups of attaching devices for said keys and the several devices of each group being indicated by identifying symbols, the symbols of one group being adapted to be brought successively opposite said index opening.

9. The combination with lines of voting

members, of primary locking mechanism including locking members for locking the voting members in the several lines, and a key carrier provided with keys for controlling said locking members to lock or unlock the voting members in any line or lines, said keys being formed with a straight portion and with an offset portion for attaching said keys to the key carrier and for engaging and operating said locking members.

10. The combination with lines of voting members, of primary locking mechanism including locking members for locking the voting members in the several lines, and a key carrier provided with keys for controlling said locking members to lock or unlock the voting members in any line or lines, said keys being formed with a straight portion and with an offset portion for attaching said keys to the key carrier, and said locking members having notches engaged by the straight and offset portions of the keys.

11. The combination with lines of voting members, of primary locking mechanism including locking members for locking the voting members, said locking members having notches, and means controllable independently of said voting members and engaging said notches for controlling said locking members to lock or unlock the voting members in any line or lines.

12. The combination with lines of voting members, of primary locking mechanism including locking members for locking the voting members, said locking members having notches, and a member controllable independently of said voting members and provided with means engaging said notches for controlling said locking members, said last named member being progressively movable to lock or unlock the voting members in any line or lines.

13. The combination with lines of voting members, of primary locking mechanism including locking members for locking the voting members, said locking members having notches, and a key carrier controllable independently of said voting members and provided with keys engaging said notches for controlling said locking members to lock or unlock the voting members in any line or lines.

14. The combination with lines of voting members, of primary locking mechanism including locking members for locking the voting members, said locking members having notches, and a key carrier provided with keys engaging said notches for controlling said locking members to lock or unlock the voting members in any line or lines, said keys being adapted for attachment to said key carrier in any desired position and arrangement.

15. The combination with lines of voting members, of primary locking mechanism in-

- cluding means for locking the voting members in the several lines, means for controlling said locking means, and a rack and pinion for operating said controlling means to lock or unlock the voting members in any line or lines. 5
16. The combination with lines of voting members, of primary locking mechanism including means for locking the voting members in the several lines, a sliding key bar for controlling said locking means, a rack on said bar, and a pinion engaging said rack for operating said key bar to lock or unlock the voting members in any line or lines. 10
17. The combination with lines of voting members, of primary locking mechanism including locking members for locking the voting members in the several lines, means for controlling said locking members to lock or unlock the voting members in any line or lines, a rack connected with said controlling means, and a pinion movable into and out of engagement with said rack for operating said controlling means. 20
18. The combination with lines of voting members, of primary locking mechanism including means for locking the voting members in the several lines, means for controlling said locking means, means detachably connected with said controlling means for operating the same to lock or unlock the voting members in any line or lines, and means for locking said operating means in engagement with said controlling means. 30
19. The combination with lines of voting members, of primary locking mechanism including means for locking the voting members in the several lines, means for controlling said locking means, means detachably connected with said controlling means for operating the same to lock or unlock the voting members in any line or lines, and a latch for locking said operating means in engagement with said controlling means. 40
20. The combination with lines of voting members, of primary locking mechanism including means for locking the voting members in the several lines, means for controlling said locking means, means detachably connected with said controlling means for operating the same to lock or unlock the voting members in any line or lines, a latch for locking said operating means in engagement with said controlling means, and a spring for holding said latch in operative position. 50
21. The combination with lines of voting members, of primary locking mechanism including means for locking the voting members in the several lines, a key bar for controlling said locking means, a shaft for operating said key bar to lock or unlock the voting members in any line or lines, said shaft being movable into and out of engagement with said key bar, and a latch for locking said shaft in operative position. 60
22. The combination with lines of voting members, of primary locking mechanism including locking members for locking the voting members in the several lines, said locking members having notches, a sliding key bar having means engaging said notches for controlling the locking members, and means for operating said key bar to lock or unlock the voting members in any line or lines. 70
23. The combination with lines of voting members, of primary locking mechanism including locking members for locking the voting members in the several lines, said locking members having notches, means engaging said notches for controlling said locking members, and means detachably connected with said controlling means for operating the same to lock or unlock the voting members in any line or lines. 80
24. The combination with lines of voting members, of primary locking mechanism including means for locking the voting members in the several lines, means for controlling said locking means to lock or unlock the voting members in any line or lines, a rack connected with said controlling means, a pinion movable into and out of engagement with said rack, and means for locking said pinion in engagement with said rack. 90
25. The combination with lines of voting members, of primary locking mechanism including means for locking the voting members in the several lines, means for controlling said locking means to lock or unlock the voting members in any line or lines, and means for yieldingly holding said controlling means in certain positions with certain lines of voting members unlocked and the remaining lines locked. 100
26. The combination with lines of voting members, of primary locking mechanism including means for locking the voting members in the several lines, means for controlling said locking means, means for operating said controlling means to lock or unlock the voting members in any line or lines, and means for yieldingly holding said operating means in certain positions with certain lines of voting members unlocked and the remaining lines locked. 110
27. The combination with lines of voting members, of primary locking mechanism including means for locking the voting members in the several lines, means for controlling said locking means to lock or unlock the voting members in any line or lines, said means including a shaft, and means for yieldingly holding said shaft in certain positions with certain lines of voting members unlocked and the remaining lines locked, said last named means including a stationary washer loose on said shaft and a second 120

- 130

washer rotatable with said shaft and longitudinally movable thereon, said washers having interengaging projections and recesses.

28. The combination with a framework and lines of voting members, of primary locking mechanism including means for locking the voting members in the several lines, means for controlling said locking means to lock or unlock the voting members in any line or lines, said means including a shaft, and means for yieldingly holding said shaft in certain positions with certain lines of voting members unlocked and the remaining lines locked, said last named means including a collar on the shaft, interengaging members on the framework and shaft respectively, and a spring interposed between said collar and the interengaging member on the shaft.

29. The combination with lines of voting members, of primary locking mechanism including locking members for locking the voting members in the several lines, a key carrier provided with means for controlling said locking members to lock or unlock the voting members in any line or lines, a cover plate for guiding said key carrier and having an index opening, said key carrier being provided with identifying symbols adapted to be brought successively opposite said in-

dex opening to indicate the line or lines of voting members which are unlocked, and means for yieldingly holding said key carrier in certain positions with said symbols 35 opposite said index opening.

30. The combination with a framework and lines of voting members, of primary locking mechanism including means for locking the voting members in the several 40 lines, a key bar for controlling said locking means, a shaft for operating said key bar to lock or unlock the voting members in any line or lines, said shaft being movable into and out of operative engagement with said key bar, a collar on said shaft, interengaging members on the framework and shaft respectively for holding said shaft in certain positions with certain lines of voting members 45 unlocked and the remaining lines locked, a spring interposed between said collar and the interengaging member in the shaft, and a latch movable to a position between said collar and the framework to lock said shaft in operative engagement 50 with said key bar.

In testimony whereof I affix my signature in presence of two witnesses.

CHARLES C. ABBOTT.
